LIFE SAVING DEVICE

Louis Wolshin, Hialeah, Fla.

Application July 12, 1954, Serial No. 442,575

6 Claims. (Cl. 9—19)

This invention relates to life saving equipment and has particular reference to such equipment that is supported upon the body of a life guard for use in the rescue of drowning persons.

An object of the invention resides in providing a pair of substantially identical inflatable devices that are foldable in a deflated condition for compact storage in a convenient belt supported pouch, whereby the devices may be conveniently carried to a point of rescue to be subsequently easily inflated and discharged from the pouch in a manner that will not interfere with the life guard promptly swimming to the point of rescue, and which will not impede his actions in inflating and presenting the life saving device to a drowning person or a person in difficulty.

A further object of the invention resides in a novel form of inflatable rescue device that is formed in two substantially identical semi-circular members and with each member being separate and independent of the other, and with each member provided with an independent inflation mechanism having a pull-cord that projects beyond the opposite ends of the pouch when the devices are in the deflated and packed condition and with the pull devices being conveniently located at a point whereby the life guard may inflate first one and then the other of the devices, depending upon the number of persons to be rescued.

A further object of the invention resides in an inflatable life saving equipment that is packed in a relatively small pouch in compact form and with the pouch being so constructed that upon the inflation of a selected inflatable device, that portion of the pouch will be automatically opened under the influence of the expansion of the device and projected in fully inflated condition whereby the life guard may present it to a person in difficulty or whereby the device may be bodily attached to the person.

The invention further contemplates an elongated tow cord that is likewise stored within the pouch with a portion thereof projecting outwardly of the pouch to be grasped by the life guard and with the tow cord being adjustable to form a body encircling loop at one end and a snap hook at the opposite end, whereby the tow cord may be conveniently snapped into engagement with a ring carried by each of the inflatable devices, thereby providing a convenient means whereby a person in difficulty may be manually towed to safety, while being supported by the inflated device.

A further object of the invention resides in novel connecting means between the two inflatable devices, whereby the devices may be used individually or connected together to form a body encircling support and with at least one of the inflatable devices being provided with a plurality of connecting means whereby the two inflatable devices when connected together may be adjustable as to their body encircling diameter to support a child or an adult.

2

A further object of the invention resides in a novel means whereby one semi-circular inflatable device and a tow cord can be employed to conveniently support an individual within the device against slipping therefrom.

5 A further object of the invention resides in novel means whereby the belt may be easily and quickly attached to the opposite free ends of either of the inflatable devices to serve as an enclosure device to prevent a person slipping therefrom.

10 Structural features of novelty and arrangement of parts will be more readily apparent during the course of the following description, reference being had to the accompanying drawings, wherein has been illustrated a preferred form of the device and wherein like characters of reference are employed to denote like parts throughout the several figures.

In the drawings:

Figure 1 is a fragmentary rear elevation of a body supported pouch wherein is supported in compact form the inflatable devices and showing the same supported upon a body encircling belt of a life guard,

Figure 2 is a perspective view of the supporting pouch and the body encircling belt,

25 Figure 3 is an enlarged view of a supporting pouch, parts being broken away for sake of clearness and showing the individual inflatable devices stored therein with their actuating cords projected beyond the ends of the pouch,

Figure 4 is an enlarged top plan view of a pair of inflated devices in separated form,

Figure 5 is a fragmentary cross-section illustrating the inflatable device in a deflated condition,

Figure 6 is a top plan view illustrating the inflatable devices connected together as a body encircling member, and

35 Figure 7 is a plan view illustrating the use of a body encircling belt as a combined body supporting guard and a tow means.

Referring specifically to the drawings, the numeral 5 designates a pouch, formed of any desirable and preferably water-proof material. The pouch is formed from a generally rectangular sheet of material whose edges are reinforced in any desirable manner with the sheet being folded upon itself as shown in Figure 2. Separable snap fasteners 6 are spaced around the marginal edges of the pouch and serve to maintain the pouch in a position to house inflatable devices, to be presently described. One wall of the pouch is provided with loops 7 that slidably receive a body encircling belt 8. The belt 8 is adjustable in length as shown at 9. One end of the belt is provided with a ring 10 and the opposite is provided with a snap hook 11. An additional ring 12 may be carried by the belt intermediate its length.

55 The numerals 13 and 14 designate a pair of substantially identical inflatable semi-circular tubes that are closed at their opposite ends. The tubes may be formed of any desirable material, such as rubber or plastic, that is calculated to withstand a desired inflation pressure.

60 Each of the tubes 13 and 14 are provided at one end with an attaching ring 15 and at its opposite end with a preferably swiveled snap hook 16. The tube 13 is preferably provided with additional rings 17, for a purpose to be presently described. Each of the tubes 13 and 14 inwardly of adjacent end portions are provided with inflation

65 devices 18. The inflation devices 18 are of conventional construction and are characterized by a tubular body portion 19 wherein is disposed the well known puncturable cartridges. The cartridges are of the type commonly employed in various life saving jackets, life boats and the like. The cartridges are maintained within the tubes 19 by removable caps 20. The tubes 19 at one end are extended to provide a pivotal point 21 for a trigger arm

22, through the medium of which the trigger arm may serve to actuate the well known mechanism for puncturing an end of the cartridge to permit a flow of its gas to the interior of the tubes 13 or 14. The trigger 22 is provided with a flexible pull cord 23 having a knob 24. The tube 10 has communication with the interior of the inflatable tubes 13 or 14, through the medium of a tubular coupling 25 that has sealed engagement through a wall of the tubes 13 and 14.

In the use of the device, the tubes 13 and 14 in the deflated condition as shown in Figure 5 are folded upon themselves into compact form with their inflation devices 18 preferably uppermost. A tow cord 26 of any desirable material is provided at one end with a preferably swiveled snap hook 27 and at its opposite end, the cord is provided with a slide device 28 through the medium of which a loop 29 may be conveniently formed and adjusted for engagement with the body of the life guard, preferably over the neck. When the tubes 13 and 14 are packed within the pouch 5, the snap hook 27 may be engaged with one of the rings 15. The major length of the tow cord 26 is likewise folded within the pouch with a portion thereof projecting therebeyond, as clearly shown in Figure 2, thus, when the device is to be employed in an emergency, the life guard may conveniently reach around and pull the tow cord upwardly and slip it over his head. After the tubes 13 and 14 are folded into compact form, they are placed upon the surface of the open pouch and the pouch then folded upon itself and the several snap fasteners 6 engaged to hold the tubes in their packed condition against accidental displacement. As the pouch is folded, the pull cords 23 are positioned so that their knobs 24 extend outwardly beyond the ends of the pouch for convenient engagement by the hand of the operator. The pouch as now fully packed and closed is engaged with the belt 8 and strapped about the body of the life guard with the pouch being disposed at the back of the life guard, preferably adjacent one side.

Now, when the life guard observes a person in difficulty, he immediately proceeds to swim toward the person in distress. He may, if desired, pull the tow cord 26 outwardly and engage the loop 29 over the shoulder or he may engage the tow cord at the point of rescue. It is important that the tubes 13 and 14 remain in the deflated condition while the life guard is swimming to the scene of rescue, thus offering no impediment to the free use of his arms and legs in traversing the distance from shore to the point of rescue in a minimum of time. Upon reaching the scene of the rescue operation, the life guard then reaches rearwardly, grasping the knob 24 and pulls it downwardly, causing the trigger 22 to puncture the cartridge within the tube 19. This permits the flow of gas into the tube 13 or 14, as the case may be, causing it to expand and, under the influence of the expansion, the snap fasteners 6 will be separated to release and project the expanded tube and its companion deflated tube. It should be here pointed out, that when the tubes are packed into the pouch, they are preferably hooked together at one end. If the person to be rescued is fully conscious, the life guard hands him the inflated tube, whereby he will be safely supported in the water. If the person is unable to maintain his hold upon the tube, the life guard may then train the tow cord 26 through the snap hook 16, it being assumed that the hook 27 is already in snap engagement with the ring 15, thus, by pulling upon the tow cord 16, the person being rescued is securely locked within the expanded tube and the life guard may proceed to tow him to shore. In the event of damage to the first tube to be expanded, the second tube is always ready for instant inflation and use. While the inflation devices 18 are provided, it is contemplated that an addition means may be provided whereby the tubes may be inflated by the mouth in the event of leakage while in use. It sometime happens that two or more

persons are in difficulty at the same time. The life guard then releases first one tube 13 and then the other tube 14 in a similar manner, presenting each of the persons in distress with an inflated tube. Now, should both persons be in distress, one person may be locked within his respective tube by the training of the tow cord 6 through the snap hook 16, as above described, and the life guard then proceeds to release the belt from his body and, by engaging the snap hook 11 within a ring 15, and the ring 12 within its companion snap hook 16, the second person may be securely locked within the tube against slipping therefrom. The life guard may then proceed to tow both persons to safety, having in mind that the loop 29 is engaged over his neck, while he may employ the extended end of the belt as a tow line for the second person; or, should he desire to have both arms free for swimming, the ring 10 may be engaged with the snap hook 16 of the tube supporting the second individual whereby the life guard may proceed to tow the two persons in tandem. Where the tubes 13 and 14 are to be employed jointly as a body encircling device, their respective rings and snap hooks 15 and 16 may be engaged as shown in Figure 6, thus forming in effect a complete ring. This is desirable for unusually large persons and the diameter of the device as in Figure 6 may be adjustable by engaging a snap hook 16 in either of the rings 17. It is desirable that the tubes and their respective inflation devices be packed and arranged so that the operation of the pull cords 23 will be in a downward direction, thus greatly facilitating the actuation of the inflation device.

It will be apparent from the foregoing that a very simple and highly effective life saving equipment has been provided. The device while shown as embodying two inflatable semi-circular tubes may obviously embody one or more if so desired. The device is so compact as to offer no resistance to the free action of the life guard in reaching the scene of distress. Life saving equipment presently in use has included a very cumbersome can device that must be towed to the point of rescue, requiring a very considerable effort of the life guard in reaching the scene of distress in a minimum of time. It is pointed out that a matter of seconds may mean the difference between a successful rescue or the death of the person in distress, and it has been found that the use of the rescue can so greatly retards the life guard in his swimming to the person in distress that much valuable time has elapsed during the towing action. This is especially true in rough weather where the waves are unusually high and frequently in attempting to tow the cans to the point of rescue, the life guard is thrown back to the point of safety. With the device of this invention, the life guard may quickly reach the scene of the accident, trip the inflation device and either present it to the person in distress or secure the device about the body of the person should he be unable to voluntarily retain his hold thereon. The device has wide use as a rescue means for life guards, may be employed as a safety measure upon aircraft, boats or the like. The structure is simple, easily packed, is cheap to manufacture, is strong, durable and highly effective for the purposes set forth.

It is to be understood that while a preferred form of the device has been illustrated and described, changes are contemplated as readily fall within the spirit of the invention as determined by the scope of the subjoined claims.

Having described my invention, what I claim as new and desire to secure by Letters Patent is:

1. A life saving device of the character described for support upon a body encircling belt carried by a life guard, a pouch supported upon the belt, a plurality of semi-circular inflatable tubes supported within the pouch in a deflated and folded condition, means carried by each of the tubes whereby the tubes may be individually inflated, means connected with the inflation means where-

by to actuate either of the inflation means and with the last named means projecting outwardly of the pouch for manual control of the inflation means, the inflation of either of the tubes causing an adjacent overlying area of the pouch to open for discharging the inflated tube, a body engaging tow cord that is housed in the pouch with a portion thereof projecting outwardly of the pouch whereby to facilitate the engagement thereof by the life guard, the tow cord provided with means for detachably connecting one end thereof with one end of either of the tubes, detachable connecting means between the tubes when in the inflated condition, and means carried by the body encircling belt that has detachable connection with the opposite ends of a tube to securely support the tube upon an individual against accidental displacement, the body encircling belt when connected to an inflated tube providing a tow line for the individual.

2. The device according to claim 1, wherein the pouch is formed of a sheet of material folded upon itself and with the marginal edges being provided with mating spaced apart separable snap-fasteners whereby the pouch is releasably held in a pouch-forming position to be separated under the influence of an expanding tube to permit the discharge of the tube, the pouch being provided with belt engaging loops upon its outer face for the reception of the body encircling belt.

3. The device according to claim 1, wherein each of the semi-circular tubes are formed of flexible and waterproof material, the ends of each tube being sealed, the said inflation means comprising a compressed gas containing cartridge holder carried by each of the tubes adjacent one end and with the holders having communication with the interior of the tubes, the holders being of a type that are provided with a trigger mechanism for the manual actuation to puncture the cartridge and inflate the tube, the detachable connecting means between the tubes being mating and with the connecting means being carried by the ends of each tube whereby the tubes may be connected together to form an enclosing ring and means for ad-

10

5

20

15

25

30

35

justably connecting adjacent ends of the tube to vary the diameter of the enclosing ring.

4. The device according to claim 3, wherein the detachable connecting means for each tube embodies a snap-hook at one end of the tube and a ring at the opposite end of the tube, one of the tubes inwardly from its ring carrying end being provided with a plurality of spaced apart rings for the selective reception of a snap-hook carried by the other tube.

5. The device according to claim 1, wherein the tow cord is provided at one end with a snap-hook whereby to provide the detachable connection with a ring carried by one end of either tube, the tow cord at its opposite end being provided with an adjustable loop for engagement with the body of the lifeguard.

6. The device according to claim 1, wherein the body encircling belt is adjustable in length, the said detachable connection between the belt and the opposite ends of a tube embodying a snap-hook that is disposed at one terminal end of the belt and a ring that is supported intermediate the ends of the belt and with the ring and the snap-hook being connected to the opposite ends of a tube through the medium of the said detachable connecting means of the tube.
